(57) **CLAIM**

The ornamental design for a corset for concealed firearms, as shown and as described.

DESCRIPTION

FIG. 1 is a front perspective view of a corset for concealed firearms showing my new design wherein the corset for concealed firearms is shown in an open, unfastened form; FIG. 2 is front view thereof; FIG. 3 is a back view thereof; FIG. 4 is a left view thereof; FIG. 5 is a right view thereof; FIG. 6 is a top view thereof; FIG. 7 is a bottom view thereof; FIG. 8 is a front view thereof showing the corset for concealed firearms in a closed, fastened form; FIG. 9 is a front view showing an exemplary use with an exemplary firearm positioned at a front of the corset within a flap of the corset; and, FIG. 10 is a front view showing an exemplary use with an exemplary firearm positioned at a side of the corset within a flap of the corset, whereby firearms can be positioned all around the corset in any orientation as desired within the flap of the corset.

The broken lines included in the Figures illustrate environmental structure and form no part of the claimed design.
